UNITED STATES PATENT OFFICE

2,506,060

APPARATUS FOR STRIPPING INSULATION

Guilford F. Branson, Pampa, Tex.

Application September 16, 1946, Serial No. 697,372

2 Claims. (Cl. 81—9.51)

1

This invention relates to apparatus for stripping insulation, and has for its primary object to remove the insulation from a length of insulated conductor.

In the electrical arts electrical conductors are commonly encased in an insulating sheath conventionally composed of rubber and fabric and when it becomes necessary to connect two or more lengths of conductor together or to effect an electrical connection to a piece of apparatus a portion of the insulating sheath must be removed to expose a portion of the conductor for contact with the adjacent conductor or the apparatus. The process of stripping the insulation from a conductor becomes increasingly laborious as the size of the conductor increases, with the result that much labor is spent and time is consumed in effecting such connections.

Another object of this invention is to easily and quickly the insulation from a length of insulated conductor.

The above and other objects may be attained by employing this invention which embodies among its features advancing an insulated conductor in a rectilinear path, while it is being so advanced exerting sufficient pressure on opposite sides of the insulation to cause the conductor to cut through and separate the insulation into two strips, leaving the conductor free of insulation.

Other features include an inclined guide and means to advance an insulated cable in a rectilinear path through the guide to cause the conductor in the cable to cut through and form diametrically opposed longitudinal incisions in the insulation whereby the latter easily may be stripped from the conductor.

Still other features include a pair of feed rolls to advance the cable through the guide, a pair of drafting rolls cooperating with the feed rolls to advance the cable in a rectilinear path through the guide, means to drive the rolls in unison and means simultaneously to adjust the space between the feed rolls and the space between the draft rolls.

In the drawings:

Figure 1 is a plan view of an insulation stripper embodying the features of this invention;

Fig. 2 is a front view in elevation of Figure 1;

Fig. 3 is an end view of Fig. 1;

Fig. 4 is a fragmentary rear view of Fig. 1;

Fig. 5 is an enlarged sectional view taken substantially on the line 5—5 of Fig. 2;

Fig. 6 is a fragmentary sectional view taken substantially on the line 6—6 of Fig. 5;

Fig. 7 is an end view of Fig. 6;

2

Fig. 8 is a perspective view of one of the roller supports;

Fig. 9 is a perspective view of the adjusting yoke, and

Fig. 10 is a perspective view of a roller carriage.

Referring to the drawings in detail, a base 15 has mounted adjacent one end a prime mover 16 which in the example shown takes the form of an electric motor which is equipped with a flexible cord 17 equipped with a conventional attachment plug 18 and switch 19.

Secured to the base 15 adjacent the prime mover 16 are conventional speed reduction gears housed within a housing 20. These are coupled by a shaft 21 to the prime mover 16 so that when the latter is energized the speed reduction gears will be set into motion to drive the shaft 22 (Figs. 5 and 6).

Mounted on the base 15 immediately adjacent the speed reduction gears is the stripping mechanism, designated generally 23, which includes a pair of spaced parallel roller supports 24, each of which comprises a substantially rectangular plate formed near its upper end with a pair of spaced openings 25 and 26 (Fig. 8), arranged in the same horizontal plane and formed immediately below the openings 25 and 26 are elongated openings 27 and 28, respectively. Extending into the plate 24 from its lower edge and opening into the lower end of the openings 27 and 28 respectively, are slots 29 and 30 for the reception of the legs of the elevating yoke to be more fully hereinafter described.

Fitted in the openings 25 and 26 are bearing bushings in which the shafts 22 and 32 respectively are mounted to rotate. The shaft 32 has keyed or otherwise fixed to it a feed roll 33, the periphery of which is formed with spaced longitudinal grooves 34, and the face of the roll between the grooves is knurled as at 35 (Fig. 6). Keyed or otherwise secured to the shaft 22 is a draft roll 33', the periphery of which is smooth.

As illustrated in Fig. 6 the shafts 22 and 32 extend through the bushings 31 beyond the outermost support 24 and keyed or otherwise secured to these extensions are pinions 36 and 37, respectively.

A pinion 38 is mounted to rotate about a stud 39 carried by the outermost plate 24 in such a position as constantly to mesh with the pinions 36 and 37, whereby, when the shaft 22 is driven, the shaft 32 will be driven in the same direction.

Mounted to slide vertically in the openings 27 and 28 are bushings 40, in which shafts 41 and 42 are rotatably mounted. Keyed or otherwise

secured to the shaft 41 is a draft roll 43, while a feed roll 44 is keyed to the shaft 42. The periphery of the feed roller 44 is knurled as at 45 (Fig. 6). Like the shafts 22 and 32 the shafts 41 and 42 extend beyond the outermost plate 24 and keyed or otherwise secured to these shafts are pinions 46 and 47 respectively. These pinions mesh with a pinion 48 which is mounted to rotate about a stud 49 carried by the outer face of the outermost support 24, and this pinion 48 is so located as to be in constant mesh with the pinion 38. It will thus be seen that when the shaft 22 is set into motion the feed rollers 33 and 44 and the draft rolls 33' and 43 will be driven in unison.

In order to advance the rolls 43 and 44 upwardly toward the rolls 33' and 33, respectively, wedge members 50 and 51 are mounted on the base 15 to slide through the slots 29 and 30, respectively, and resting on the upper inclined edge of each wedge member is a carriage designated generally 52 (Fig. 10). Each carriage comprises a base plate 53 having an inclined under face 54, which coincides with the upper inclined edge of its respective wedge member so that as the wedge members are moved longitudinally through the slots 29 and 30 the carriages 52 will be raised or lowered. Extending upwardly from each end of the base 53 of each carriage 52 is a flange 55, and each flange is formed with a centrally disposed arcuate recess 56, to receive a bushing 40. Extending transversely between the reduced ends of the wedge members 50 and 51 is a cross bar 57 (Fig. 9) and formed midway between opposite ends of the cross bar is an internally screw threaded opening 58 for the reception of a longitudinally extending screw threaded shaft 59. The outer end of this shaft is provided with a squared extension 60, while its opposite end is mounted for rotation in the outermost plate 24 but held against longitudinal movement. It will thus be seen that when the shaft 59 is rotated the cross bar 57 and wedge members 50 and 51 will be moved longitudinally of the base 15.

Detachably secured as at 60' to the rear edge of the base 53 of the carriage 52 in which the shaft 41 is supported, is a scraper blade 61 carrying an adjusting screw 62, the end of the shank of which bears against an angle bracket 63 carried by the aforesaid carriage. The scraping edge of the blade is sharpened as illustrated in Fig. 5 and is adapted to bear against the periphery of the roller 43 to scrape any debris therefrom.

A cover 64 encloses the top and front of the stripping mechanism extending over the upper and front edges of the plates 24 and formed in the front vertical wall of this cover 64 is an opening 65 in which a guide bushing 66 is fitted. The axis of this guide bushing 66 lies substantially tangent to the bottom of the periphery of the feed roll 33 so that a cable to be stripped when introduced into the bushing will encounter the periphery of the feed roll and be fed thereby into the machine.

Carried by the rear edge of the cover 64 and lying in a vertical plane substantially tangent to the draft roll 33' is a depending tongue 67 to which a scraper blade 68 is detachably secured as by an attaching screw 69. This blade carries an adjusting screw 70, the end of the shank of which bears against an angle bracket 71 secured to the upper face of the top of the cover 64 immediately above the tongue 67. The lower edge of the blade 68 is sharpened and is adapted to

bear on the periphery of the roll 33' to scrape any debris from the peripheral surface thereof.

Supported substantially midway between the rolls 33 and 33' is an angle guide designated generally 72 which comprises a tubular body 73, having a smoothly rounded mouth 74 into which the conductor to be stripped from its insulation is introduced. The lower portion of the mouth 74 of the tubular body 73 lies in alignment with the upper portion of the feed roll 44 and the axis of the tubular guide 73 inclines downwardly toward the rear end of the machine so that the upper portion of the rear end of the guide 73 aligns with the lower portion of the draft roll 33'. Hence as an insulated cable is advanced by the rolls in a rectilinear path through the guide 73 pressure will be exerted on the insulating sheath and cause it to be squeezed against the conductor. Such squeezing of the sheath will cause the conductor to slit the sheath and facilitate the separation of the sheath from the conductor.

Suitable oil ducts 74' lead from the bearing bushings 31 and 40 upwardly through openings in the cover 64 adjacent the plates 24 so that the shafts operating in the bushings may be easily lubricated.

In use it will be understood that the attachment plug 18 is entered into a convenient electric power outlet and upon closing the switch 19 the motor 16 will be set into operation, thus driving the shaft 21 and the train of speed reduction gears in the housing 20. This will drive the shaft 22 and thence through the medium of the gear 36 the gears 38 and 48 will be set in motion. Through the medium of the gears 37 and 47 the shafts 32 and 42 of the feed rolls 33 and 44 will be driven so that an insulated conductor introduced into the machine through the bushing 66 will be directed into the mouth 74 of the angle guide 72. Simultaneously with the driving of the feed rolls and the draft roll 33', the draft roll 43 will be driven through the gear 46, so that the cable emerging from the angle guide 72 will be gripped by the draft rolls 33' and 43 and advanced in a rectilinear path through the angle guide 72. The advance of the cable in the rectilinear path will cause the insulation on the cable to contact the angle guide on opposite sides so as to press the insulation toward the conductor and cause the conductor to cut through the insulation and form longitudinal slits or incisions therein, with the result that the insulation may be easily stripped from the conductor or conductors. The distance between the feed rolls 33 and 44 and the distance between the draft rolls 33' and 43 may be varied by turning the threaded shaft 59 to move the wedge members 50 and 51 and thus raise or lower the carriages 52. It will thus be seen that the machine may be employed to strip cable of varying sizes.

While in the foregoing there has been shown and described the preferred embodiment of the invention, it is to be understood that minor changes in the details of construction, combination and arrangement of parts may be resorted to without departing from the spirit and scope of the invention as claimed.

I claim:

1. In an insulation stripper of the type having spaced pairs of rolls between which a conductor is moved in a rectilinear path, means for removing an insulating sheath from said conductor as it is moved by the rolls, said means comprising an elongated tubular guide member mounted between

said pairs of rolls in encircling relation to the conductor, said guide member lying along an inclined axis which intersects the rectilinear path, and the upper portion of the guide member adjacent one end thereof aligning with the lower portion of the upper roll of one pair of rolls while the lower portion of the guide member adjacent the opposite end thereof aligns with the upper portion of the lower roll of the opposite pair of rolls and forcing the sheath to be split by the conductor. 10

2. In an insulation stripper of the type having spaced pairs of rolls between which a conductor is moved in a rectilinear path, means for removing an insulating sheath from said conductor as it is moved by the rolls, said means comprising an 15 elongated tubular guide member mounted between said pairs of rolls in encircling relation to the conductor, said guide member lying along an inclined axis which intersects the rectilinear path, substantially midway between the spaced pairs of rolls, and opposite portions of said guide member adjacent opposite ends thereof aligning with the lower roll of one pair of rolls and the upper roll of the opposite pair of rolls respectively whereby 20

as the conductor is moved opposite sides of the sheath will be pressed toward the conductor and slit thereby.

GUILFORD F. BRANSON.
